Earl D. Myers, Scotch Plains, N.J., assignor to Ohaus
Scale Corporation, Union, N.J., a corporation of New
Jersey

Filed Aug. 16, 1961, Ser. No. 66,372

Term of patent 14 years

(Cl. D52—10)

FIG. 1

FIG. 2

FIG. 3

FIG. 4

FIG. 5

FIG. 1 is a front elevational view of a casing for storing and mounting a knock-down weighing scale, in closed condition, showing my new design.

FIG. 2 is a left end elevational view thereof.

FIG. 3 is a front elevational view thereof with the cover removed.

FIG. 4 is a top plan view thereof with the cover removed.

FIG. 5 is a top perspective view thereof with the cover removed.

The undisclosed end of the casing is a mirror image of the end disclosed in FIG. 2, and the rear is substantially plain in appearance.

The broken line portions in FIG. 3 represent disassembled scale parts in stored positions, and are shown for illustrative purposes only.

I claim:

The ornamental design for a casing for storing and mounting a knock-down weighing scale, as shown and described.
